[57] ABSTRACT

In a heating roller of the class comprising a cup-shaped cylindrical roller having a closed bottom, a driving shaft for rotating the roller connected to the center of the bottom and extending coaxially through the cylindrical roller, a stationary bobbin supported within the cylindrical roller coaxially with the driving shaft, the bobbin having an inner flange facing to the bottom and an outer flange close to the open end of the cup-shaped cylindrical roller, and an induction coil wound about the bobbin for inductively heating the cylindrical roller, there are provided a radially extending flange at the open end of the cup-shaped cylindrical roller and a surrounding annular ring connected to the periphery of the outer flange to surround the radially extending flange.

HEATING ROLLERS WITH AXIAL MAGNETIC FORCE REDUCTION MEANS

BACKGROUND OF INVENTION

1. Field of Invention

This invention relates to an improved construction for a heating roller adapted to heat synthetic fibers or strings which are required to be heat treated at a constant temperature.

2. Prior Art Problem

As shown in FIG. 1, a conventional heating roller utilized for this purpose comprises a cup-shaped cylindrical roller 1 having one end (left hand end as viewed in FIG. 1) closed and provided with a driving shaft 2 connected to the center of the bottom. Although not shown in the drawing, the shaft 2 is supported by a bearing and connected to a source of drive. The inner surface of the cylindrical roller 1 is covered by a heat generating layer 3 of conductive material. A cylindrical bobbin 4 having an inner flange 4₁ and an outer flange 4₂ is provided to concentrically surround driving shaft 2. The outer diameter of inner flange 4₁ is made smaller than the inner diameter of the cylindrical roller 1 whereas the outer flange 4₂ has an outer diameter substantially equal to that of the cup-shaped cylindrical roller 1 and is positioned opposite the open end thereof with a small gap *g* therebetween. On the outside of the bobbin 4 are mounted a laminated magnetic core 5 and an induction coil 6 which is energized by a source of alternating current (not shown). The cylindrical roller 1 and outer flange 4₂ are made of magnetic material so as to form a substantially closed magnetic circuit.

When the induction coil 6 is energized from the source of AC, magnetic flux is induced to flow through the magnetic path indicated by dotted lines thereby heating the cylindrical roller by the eddy current loss and hysteresis loss produced therein, the heating being assisted by the short circuit current induced in the heat generating layer 3.

With the construction shown in FIGS. 1 and 2, however, due to the attractive magnetic forces created across the gap *g*₁ between the opening of the cylindrical roller 1 and the outer flange 4₂ and the gap *g*₂ between the inner bottom surface of the cylindrical roller 1 and the inner flange 4₁ of the bobbin 4, thrust loads act upon the shaft 2 in the directions shown by arrows *a*₁ and *a*₂. Since these thrust loads operate cumulatively, the shaft will be biased by the resultant of these thrust loads to the right as viewed in FIG. 1.

The attractive forces *F*₁ and *F*₂ at gaps *g*₁ and *g*₂ are given by the following equations.

$$F_1 = (S_1 Bm_1^2 / 2\mu_0) [N] \quad F_2 = (S_2 Bm_2^2 / 2\mu_0) [N]$$

where *S*₁ and *S*₂ represent the cross-sectional areas of the magnetic path at the gaps *g*₁ and *g*₂, respectively, *Bm*₁ and *Bm*₂ the flux densities at the gaps *g*₁ and *g*₂, and μ_0 the permeability of air.

The resultant *F* of these attractive forces, that is the thrust load acting upon shaft 2 in the direction of the arrows is expressed by the following equation.

$$F = F_1 + F_2 = (1/2\mu_0) (S_1 Bm_1^2 + S_2 Bm_2^2) [N]$$

Accordingly, when the induction coil 6 is energized by a sine wave alternating current, the thrust load fluctuates sinusoidally and can result in damaging the bearing of the shaft 2. Where the bearing is damaged heavily, the coil 6 also might be damaged.

SUMMARY OF INVENTION

It is an object of this invention to provide an improved heating roller which is free from the axial thrust described above.

Accordingly, to this invention there is provided a heating roller of the class comprising a cup-shaped cylindrical roller having a closed bottom, a driving shaft connected to the center of the bottom and extending coaxially through the cylindrical roller, a stationary bobbin contained in the cylindrical roller coaxially with the driving shaft, the bobbin having an inner flange facing the bottom and an outer flange close to the open end of the cup-shaped cylindrical roller, and an induction coil wound about the bobbin for inductively heating the cylindrical roller. The invention is characterized in that there are provided a radially extending flange at the open end of the cup-shaped cylindrical roller and a surrounding annular ring connected to the periphery of the outer flange and surrounding the radially extending flange.

BRIEF DESCRIPTION OF DRAWINGS

In the accompanying drawings:

FIG. 1 shows a longitudinal section of a prior art heating roller;

FIG. 2 shows an end view of the prior heating roller shown in FIG. 1;

FIG. 3 shows a longitudinal section of an improved heating roller according to the present invention; and

FIG. 4 is an end view of the improved heating roller shown in FIG. 3.

DESCRIPTION OF THE PREFERRED EMBODIMENT

FIGS. 3 and 4 show one embodiment of the present invention in which portions corresponding to parts of the heated roller shown and described with relation to FIGS. 1 and 2 are designated by the same reference characters. In this embodiment, the cylindrical roller 1 is provided with a radially extending flange 1₁ at its open end and the outer diameter of the outer flange 4₂ of the bobbin 4 is considerably larger than that of the flange 1₁. A surrounding annular ring 7 having a cross-sectional configuration of a letter L is secured to and extended as part of the outer end of flange 4₂ to surround the flange 1₁. The axial gaps between flanges 1₁ and 4₂ and 1₁ and 7 are represented by *g*₂ and *g*₁, respectively, while the axial gap between the bottom of the roller 1 and the inner flange 4₁ of bobbin 4 is represented by *g*₃. The flange 1₁ and annular ring 7 are also made of magnetic material to form a magnetic path indicated by dotted lines.

With this construction, the attractive forces *F*₂ and *F*₃ at the gaps *g*₂ and *g*₃ create thrust loads in the direction of arrow *b* just in the same manner as in the construction shown in FIG. 1. However, the attractive force *F*₁ at gap *g*₁ operates in the opposite direction as shown by arrow *C*. Thus the force *F*₁ counteracts the sum of the forces (*F*₂ + *F*₃). These attractive forces are given by

$$F_1 = (S_1 Bm_1^2 / 2\mu_0) [N], \quad F_2 = (S_2 Bm_2^2 / 2\mu_0) [N]$$

$$F_3 = (S_3 Bm_3^2 / 2\mu_0) [N]$$

The relation *F*₁ + *F*₂ = *F*₃ can be readily satisfied by varying the cross-sectional areas *S*₁, *S*₂ and *S*₃ of the

magnetic paths or the flux densities B_1 , B_2 and B_3 at the respective gaps g_1 , g_2 and g_3 by appropriate spacing of the gaps. For this purpose, g_2 and g_3 may have a greater spacing than g_1 .

With the improved construction, since the flange 1₁ of the roller 1 is surrounded by the inturned L-shaped ring 7, the heated air inside the cylinder is retained therein thus improving the heat efficiency of the heating roller.

As above-described according to this invention there is provided an improved heating roller wherein the thrust acting upon the driving shaft can be eliminated or substantially reduced by simple means.

While the invention has been shown and described in terms of a preferred embodiment it will be clear that many changes and modifications may be made without departing from the true spirit and scope of the invention as defined in the appended claims.

What is claimed is:

1. In a heating roller of the class comprising a rotatable cup-shaped cylindrical roller having a closed bottom, a driving shaft connected to the center of the bottom and extending coaxially through said cup-shaped cylindrical roller for rotating said roller, a stationary bobbin supported within said cup-shaped cylindrical roller coaxially with said driving shaft with said roller being freely rotatable relative to said bobbin, said bobbin having an inner flange facing said bottom and an outer flange close to the open end of said cup-shaped cylindrical roller, and an induction coil wound about said bobbin for producing magnetic lines of flux magnetically coupling said bobbin and said roller through said flanges for inductively heating said cylindrical roller, the improvement which comprises, a radially extending flange secured to the open end of said cup-shaped cylindrical roller and a surrounding annular ring connected to the periphery of the outer flange of said bobbin and surrounding said radially extending flange for producing counter-balancing magnetic

forces acting between the roller and the bobbin.

2. A heating roller according to claim 1 wherein a short circuited conductive ring is provided on the cylindrical surface of said cup-shaped cylindrical roller to induce heating current.

3. A heating roller according to claim 1 wherein the air gap between the bottom of said cup-shaped cylindrical roller and said inner flange of said bobbin and the air gap between said radially extending flange of said cylindrical roller and the outer flange of said bobbin create axial magnetic forces acting in the same direction and the air gap between said surrounding annular ring and said radially extending flange creates an axial magnetic force counteracting said first mentioned magnetic forces.

4. A heating roller according to claim 3 wherein at least the air gap between the radially extending flange of the cylindrical roller and the outer flange of the bobbin is greater than the air gap between the surrounding annular ring and the radially extending flange.

5. A heating roller according to claim 3 wherein a short circuited conductive ring is provided on the cylindrical surface of said cup-shaped cylindrical roller to induce heating current, the surrounding annular ring has a cross-sectional configuration of a letter L with the bottom of the L-shaped ring opposing and acting against the bottom side of the radially extending flange on said roller.

6. A heating roller according to claim 6 wherein at least the air gap between the radially extending flange of the cylindrical roller and the outer flange of the bobbin is greater than the air gap between the surrounding annular ring and the radially extending flange.

7. A heating roller according to claim 1 wherein the surrounding annular ring has a cross-sectional configuration of a letter L with the bottom of the L-shaped ring opposing and acting against the bottom side of the radially extending flange on said roller.
